UNITED STATES PATENT OFFICE.

ROBERT WARNOCK, OF BLOOMFIELD, NEW JERSEY, ASSIGNOR TO EMPIRE CREAM SEPARATOR COMPANY, OF BLOOMFIELD, NEW JERSEY, A CORPORATION OF NEW JERSEY.

AIR-PUMP.

1,396,079.

Specification of Letters Patent.

Patented Nov. 8, 1921.

Application filed November 17, 1916. Serial No. 131,832.

To all whom it may concern:

Be it known that I, ROBERT WARNOCK, a citizen of the United States, residing in Bloomfield, county of Essex, and State of New Jersey, have invented certain new and useful Improvements in Air-Pumps, of which the following is a specification.

This invention relates to pumps for handling fluids, such as air or other gases or vapors, and is particularly applicable to vacuum or suction pumps, although the invention may in some cases be applied to compression pumps.

In pumps of the character referred to, as heretofore constructed, it has been common to form both the inlet and outlet ports in the cylinder head, which also carried the inlet and outlet valves. Quite complicated cylinder head constructions have been the result.

In some cases this practice has been departed from to the extent of putting one of the valves in the head and the other in the piston, but this arrangement involves the use of special constructions for both the cylinder and piston.

In accordance with the present invention, I provide that both the inlet and exhaust valves shall be carried on the piston, thereby entirely eliminating any mechanism on the cylinder head. The invention of the present application is also particularly well adapted to carrying out the broad invention set forth in my application, Serial No. 105,014, filed June 21st, 1916, in accordance with which I provide for the exhaust taking place through the crank case of the pump, so as to utilize the crank case as a muffler and to provide for the recovery of any lubricant carried off in the exhaust. By carrying the exhaust into the crank case, such lubricant is returned to the oil reservoir thereof, so that it may be used over again. Objectionable discharge of oil from the pump is prevented and it is possible to utilize an excess of lubricant, so as to insure adequate lubrication at all times. For these reasons the pump is particularly adapted for use by unskilled operators as the quantity of oil supplied to the pump need not be accurately gaged, it being only necessary to see that a considerable quantity is maintained at all times in the crank case. With pumps in which the discharge takes place in the open

air, it is impossible to maintain an excess of oil in the pump as it is being continually carried off and wasted. Moreover, the discharge of the oil from the pump is objectionable and therefore tends to encourage the operator to utilize an inadequate supply so as to avoid the objectionable discharge of the same.

In the accompanying drawings which form a part of this specification, I have illustrated one preferred embodiment of my invention in order to exhibit the principle of the same and the best mode now known to me for carrying it out, but I do not intend to be understood as thereby limiting myself to the details of construction set forth.

In these drawings, Figure 1 is a vertical sectional view through the pump cylinder, piston and upper part of the crank case. Fig. 2 is a horizontal section on line II—II of Fig. 1. Fig. 3 is a horizontal section on line III—III of Fig. 1. Fig. 4 is a horizontal section on line IV—IV of Fig. 1.

Referring to the drawings in detail, the numeral 1 designates the crank case of the pump, the upper part only of which is shown. As will be understood this crank case contains the bearings for the crank shaft (not shown) and is formed to provide in its lower part an oil reservoir from which the oil is fed by the splashing of the crank and connecting rod into the same in a well-understood manner. Mounted on the crank case is the cylinder 2 in which reciprocates the piston 3, the latter being connected to the crank by the connecting rod 4. The cylinder 2 is provided with a suitable head such as the simple plate 5, secured in position by the cap screws 6. If desired, the head and cylinder may be formed integral. At a suitable point between the ends of the cylinder, an enlargement 7 is formed thereon which contains an annular inlet chamber 8 having a suitable opening or openings 9 into which the inlet pipe or pipes (not shown) lead. A number of inlet ports 10 are formed in the cylinder wall and communicate with the chamber 8.

The piston 3 has an annular depression 11 formed in its periphery between the ends thereof and adapted to communicate with the chamber 8 through the ports 10 in all positions of the piston. The depression 11 also communicates through the passages 12

in the upper part of the piston wall with the inlet ports 13 formed in the valve seat 14 at the top of the piston. The piston is hollow and has an opening at its upper end, which is closed by the plate or piston head 15, which is secured to the piston in any suitable manner as by means of the screws 16 engaging lugs 17 projecting inwardly from the piston wall. An inlet valve in the shape of a flat ring 17 of thin metal is adapted to seat upon the valve seat 14 and close the ports 13 and is retained in position in a recess 18 formed in the underside of the plate 15. Springs 19 may, if desired, be provided for urging the valve upon its seat, these springs being retained in pockets 20 formed in the plate. The plate 15 also has formed through it the discharge passages 25 by which the fluid in the cylinder above the piston is discharged through the hollow piston into the crank case. These discharge passages are closed by a flat ring valve 26 adapted to seat upwardly against the valve seat 27 formed on the underside of the plate, the valve being retained in position by a retaining spider 28 secured to the plate in any suitable manner as by means of a screw 29. The valve is normally urged against its seat by springs 30 carried in pockets 31 in the spider. The cylindrical portion 32 of the spider forms a guide and centering device for the valve 26.

With the construction shown, it will be seen that on the down stroke of the piston a reduction in pressure will be produced in the cylinder above the piston, which will cause the discharge valve 26 to close upon its seat and at the same time air will be drawn in through the openings 9 into the chamber 8 and will pass through the ports 10 into the depression 11, through the passages 12 and ports 13, and so into the cylinder. On the up stroke of the piston, the pressure created in the cylinder will cause the valve 17 to close and the valve 26 to open, thus discharging the air through the piston in the crank case.

While I have shown in the drawings and described in detail, but one preferred embodiment of my invention, this is to be understood merely as illustrative of the principle of the invention and I do not, therefore, intend to limit myself to this construction, but intend to cover my invention broadly in whatever form it may be embodied.

Having thus described my invention, I claim:

1. In apparatus of the character described,

the combination of a cylinder having an inlet port in the side wall thereof between the ends of the cylinder, a piston reciprocating in said cylinder and having an elongated depression in the surface communicating at all times with said inlet port, a passage-way in said piston communicating with said depression, an inlet valve governing the passage of fluid through said passage-way and an exhaust valve on said piston.

2. In apparatus of the character described, the combination of a cylinder having an inlet port in the side wall thereof between its ends, a piston reciprocating in said cylinder and having an elongated depression communicating with said port, a passage-way in said piston connected with said depression, an inlet valve carried by said piston and adapted to close said passage-way, a discharge opening in said piston adapted to permit the passage of air from one side to the other thereof and a discharge valve adapted to close said discharge opening.

3. In apparatus of the character described, the combination of a cylinder, an inlet port formed in the side wall thereof between the ends of the cylinder, a piston reciprocating in said cylinder and having an elongated depression adapted to communicate at all times with said port, a valve seat on the end of said piston, passage-ways in said piston connecting said depression with said valve seat, an annular valve adapted to close said passage-ways, a plate attached to the end of said piston and adapted to retain said annular valve in position, said plate having a discharge port formed therethrough and a discharge valve adapted to close said discharge port.

4. In apparatus of the character described, the combination of a cylinder having an annular chamber formed around the outside thereof between the ends of the cylinder, an inlet port formed in the side wall of the cylinder and opening into said annular chamber, a hollow piston reciprocating in said cylinder and having an annular depression between its ends adapted to communicate at all times with the port in the cylinder wall, said piston having a valve seat at one end thereof, passage-ways connecting said depression with said valve seat, a valve adapted to seat on said valve seat and close said passage-ways, a plate attached to the end of the piston and adapted to retain said valve in position, a discharge port in said plate and a discharge valve adapted to close said port.

ROBERT WARNOCK.
